UNITED STATES PATENT OFFICE

121,955

DESIGN FOR AN ELECTRICAL TREATMENT APPARATUS CABINET

Joan Almon Higgins, Northfield, Ohio

Application December 28, 1939, Serial No. 89,176

Term of patent 3½ years

To all whom it may concern:

Be it known that I, Joan Almon Higgins, a citizen of the United States, residing at Northfield, in the county of Summit and State of Ohio, have invented a new, original, and ornamental Design for an Electrical Treatment Apparatus Cabinet, of which the following is a specification, reference being had to the accompanying drawing, constituting a part thereof.

Fig. 1 is a view in perspective of an electrical treatment apparatus cabinet showing my new design and

Fig. 2 is a view in perspective of the top portion of the cabinet shown in Fig. 1.

The rear or underneath portion of the cabinet not shown in Fig. 1 is a plain flat surface while the beaded ornamentation on the invisible portion of the lower right hand corner is like that shown on the diagonal upper left hand corner. The right hand side of the device shown in Fig. 1 is otherwise plain.

I claim:

The ornamental design for an electrical treatment apparatus cabinet, substantially as shown and described.

JOAN ALMON HIGGINS.
